UNITED STATES PATENT OFFICE.

JOSEPH A. BLONDIN, OF LOS ANGELES, CALIFORNIA.

AEROPLANE CONSTRUCTION.

1,240,812.

Specification of Letters Patent. Patented Sept. 25, 1917.

Application filed May 18, 1916. Serial No. 98,831.

To all whom it may concern:

Be it known that I, JOSEPH A. BLONDIN, a citizen of the United States, residing at Los Angeles, in the county of Los Angeles and State of California, have invented certain new and useful Improvements in Aeroplane Constructions, of which the following is a specification.

This invention relates to aeroplane constructions and has for its object to provide a knock-down plane having few parts of such simple construction that it may be quickly assembled even by a novice.

Another object of the invention is to provide an aeroplane having a more rigid entity of construction than those in common use whereby the main load carrying parts and auxiliary control parts are maintained in a more positive and fixed rigid relation to each other.

Another object of the invention is to provide struts for spacing the wings, the parts of which are integrally connected or formed in a single unit.

Still another object of the invention is to provide an aeroplane frame formed of rigid or integrally formed frame units upon which the entire structure is mounted.

Another principal object of the invention resides in the bracing of the frame structure relative to the wing or plane structure by arcuate skid braces interior and exterior of the skids.

My invention has for particular objects, then, the provision of improved aeroplane construction, which will be superior in point of relative simplicity, and inexpensiveness, organization, facility of attachment and detachment, positiveness and permanence of form in operation, compactness, strength and durability, and which will be slightly in appearance, and generally superior in efficiency and serviceability.

With the above and other objects in view which will hereinafter be more fully explained, I have invented the aeroplane illustrated in the accompanying drawings in which—

Figure 1 is a perspective view of my aeroplane,

Fig. 2 is a top plan view,

Fig. 3 is a front elevational view,

Fig. 4 is a side elevation,

Fig. 5 is a detailed elevational view of a frame member and

55

Fig. 6 is a similar view of a strut.

Fig. 7 is an elevational sectional view, certain parts being broken away, of a modified form of frame structure.

Like reference characters indicate like parts throughout the following specification and in the several views in the drawings.

The aeroplane consists of a pair of vertical frames 1 and 2, upper and lower main sustaining planes 3 and 4, a series of struts 5, head and tail elevating planes 6 and 7, arcuate braces 8, 9, and 10, a truck 11, propeller 12, keel 13, rudder 14, a car 15 and a tail plane 16.

Of especial importance in this invention is the construction of the side frames, the struts and the arcuate skid braces. The side frames, as before stated, are two in number and each consists of a U-shaped vertical frame member 17, to the upper ends of which is secured the horizontal outrigger frame member 18 and to the intermediate part of which is secured the lower outrigger frame member 19, the latter extending forwardly as well as rearwardly of the member 17 and to the opposite ends 19' and 20 of which the superposed arcuately formed brace members 21 and 22 are fixed; these members are also fixed to the member 17 at intersecting points therewith. The lower arcuate member 22 forms a skid or runner and this member is braced to the U-shaped member 17 by means of an arcuate brace 10. Uprights 23 and 24 connect the rear parts of the rods 18 and 19 and are themselves connected by horizontal bars 25. The above described members 17 to 25 inclusive are fixedly connected and form one unit of the frame structure upon which the main planes are mounted.

The frames of the planes 3 and 4 are rigidly spaced apart by means of struts or wing spacers 5 consisting of vertical bars 27 and 28 rigidly or integrally connected at the upper and lower ends by transverse bars 29 and 30 which are formed arcuate if required to conform to the arc of the lower surface of the upper plane and the upper surface of the lower plane. These struts are spaced suitable distances apart and may be connected by bolts or in any other suit-

able manner to the plane frames and are connected by crossed braces 31 and 32 which may either be flexible such as wire or cable guys or rigid rods.

5 For the purpose of making a more rigid structure, I provide arcuate inner skid braces 8 which connect the skid structures and lower plane frame between the skids, and arcuate braces 9, which connect the 10 outer sides of said skids to parts of said lower plane frame outwardly of frame units 1 and 2. The truck 11 includes the axle 33 and wheel 34 and 35, said axle being mounted upon said skid members and is bent upwardly at its center portion and connected to the lower plane frame by the loop 36 in which it is vertically slidable. The ends 15 of said axle project through vertical slots 48 and 49 in the braces 8 and 8 permitting relative movement between the axle and frame structure. Loop springs 50 are looped over the main parts 51 of the axle ends and are carried under the skids and then again looped over the outer ends 52 of 20 said axle whereby the axle is held normally in its lowermost position in said slots 48 and 49 and will form shock absorbers when the machine alights. The elevating plane 6 is mounted upon the forward end of the 25 brace member 21 and 22 and has an actuating means 37 extending into the car 15. The members 23 to 25 of the outrigger frame form a frame for the fabric or other keel material 38. The vertical rudder 14 is 30 pivotally connected to the outrigger frame and is operated by a cable 39 from the car 15. The cable 40 operating the rear elevating plane is controlled from the car 15, independently of the forward elevating plane 35 40. The main planes may be formed in right and left sections 41 and 42 which may be connected together in any suitable manner at the inner ends. Bars 43 and 44 form the frame of the upper plane members 3 and 45 seat upon the horizontal bars 18 and 18^a and are detachably fixed thereto, and the frames of the lower plane members 4 are formed of the bars 45 and 46 which seat upon the bars 19 and are detachably fixed thereto. Bars 50 43 to 46 are further locked between the U-shaped verticals 17.

In Fig. 7 I show a slight modification of the device in which 53 and 54 are front and rear skid braces the uppermost portions of 55 which abut and are fixed to the bars 45 and 46 and the lower ends of which are affixed to the skids 22, it being understood that outer braces (similar to braces 9 in Fig. 1, but which are not shown in the view) are 60 arranged in the same manner, that is they are arranged in pairs and connect with the bars 45 and 46 and the skids 22 whereby a somewhat firmer structure is obtained.

A particular objection attaching to the 65 construction of conventional aeroplanes is

the method of connecting the struts or wings spacers, outriggers, and skid members or running-gear, to a base consisting of the wing structure of the aeroplane. Each of the elements in question being connected 70 separately and independently, and necessitating numerous auxiliary parts, braces, ties, wires, bolts, turnbuckles, etc., and skilled and careful labor in attaching and detaching said elements, auxiliary parts, 75 etc., separately and independently, and constant supervision to insure that these numerous separate and independent elements, parts, etc., are maintained in proper juxtaposition and relative alinement. 80

My invention provides a system of construction whereby the wing-spacers are consolidated into pairs of front and rear vertical members connected by horizontal top and bottom stringers, each pair forming a rigid frame attachable to and detachable from the wing-structure, in one unit; my invention embodies the same system of frame construction in the outriggers, skids and their vertical connections whereby these 90 several members are consolidated into right, and left, rigid frames, each attachable to and detachable from the wing and control surfaces, in one unit. This is a reversal of conventional practice, as by the provisions of 95 my invention, these two side frames become the bases upon which the wings, control surfaces, and running-gear are attached, instead of the wings being bases to which all other parts are separately and independently attached, as in conventional practice. 100

By the provisions of my invention the two side frames are spaced apart and interconnected in their operative position, by the wing-structures, elevator, and tail planes, 105 and these side frame units, wings, and control surfaces are further braced, strengthened, and consolidated into one compact machine by arcuate skid-braces, interior and exterior of said skids, in front and rear 110 pairs, joining said skids to the load frame or car, and to the lower wing structure of the aeroplane, respectively. In conventional practice, no skid-braces exterior of the skids are used. In some rare cases, 115 where guy-wires are extended from outside of the skid to the wing structure, the avowed purpose of said guy-wires is to neutralize the tension stresses in the lower wing structure, rather than to stiffen the skid structure. 120

Having now described my invention that which I claim to be new and desire to procure by Letters Patent is:—

1. In an air plane, a frame, upper and lower plane structures detachably mounted upon said frame, and integrally connected struts and stringers for rigidly spacing said structures. 125
2. In an airplane construction, consoli- 130

- dated (right and left) side frame units, composed of horizontal rear outriggers, vertical connecting members and arcuate horizontal braces extending fore and aft of the 5 wing emplacement, whereby said consolidated side frame units constitute bases, which support the carrying surfaces, control surfaces and running gear of the airplane.
- 10 3. In an air plane, a frame, upper and lower plane structures detachably mounted upon said frame, and integrally connected struts and stringers for rigidly spacing said structures, and skids formed by said frame.
- 15 4. In an air plane, a frame, upper and lower plane structures detachably mounted upon said frame, and integrally connected struts and stringers for rigidly spacing said structures, skids formed by said frame, said 20 frame embracing U-shaped braces.
- 25 5. In an air plane, a frame, upper and lower plane structures detachably mounted upon said frame, and integrally connected struts and stringers for rigidly spacing said structures, skids formed by said frame, said frame embracing U-shaped braces, and a truck mounted upon said skids.
- 30 6. In an airplane, a frame formed of two similarly formed units, plane structures detachably mounted upon said frame, said structures including upper and lower sustaining plane members, means for rigidly spacing said upper and lower members, said means consisting of struts and stringers integrally connected.
- 35 7. In an airplane, a knock-down frame formed of two similarly formed units, plane structures detachably mounted upon said frame, said structures including upper and lower sustaining plane members, means for rigidly spacing said upper and lower members, said means consisting of struts and stringers integrally connected, to form a single unit.
- 40 8. In an airplane, a skid and base frame formed of two similarly formed units, plane structures detachably mounted upon said frame, said structures including upper and lower sustaining plane members, means for rigidly spacing said upper and lower members, said means consisting of struts and stringers integrally connected to form a single unit, and a truck mounted upon said skids.
- 45 9. In an airplane, a skid and base frame formed of two similarly formed units, plane structures detachably mounted upon said frame, said structures including upper and lower sustaining plane members, means for rigidly spacing said upper and lower members, said means consisting of struts and stringers integrally connected.
- 50 10. In an airplane, a skid and base frame formed of two similarly formed units, plane structures detachably mounted upon said frame, said structures including upper and lower sustaining plane members, means for rigidly spacing said upper and lower members, said means consisting of struts and stringers integrally connected to form a single unit, a truck mounted upon said skids, and arcuate braces connecting said skids and lower sustaining plane members. 65
11. An airplane frame unit embracing superposed arcuate members, a steering plane frame mounted at the rear of said unit, uprights fixed transversely of said unit, means rigidly connecting said steering plane frame and uprights, a longitudinal main plane frame support connected to the opposite ends of said arcuate members, said steering plane frame and said uprights. 80
12. An airplane frame unit embracing superposed arcuate members, a steering plane frame mounted at the rear of said unit, uprights fixed transversely of said unit, means rigidly connecting said steering plane frame and uprights, a longitudinal main plane frame support connected to the opposite ends of said arcuate members, said steering plane frame and said uprights, and arcuate braces connecting certain of said arcuate members and said uprights. 90
13. An airplane frame unit embracing superposed arcuate members, one of which forms a skid, said unit being oblong and embracing a U-shaped member mounted transversely thereof, a main plane frame support, a steering plane frame, and a brace rod parallel with said support, all of said members being in a common vertical plane. 100
14. An airplane frame unit embracing superposed arcuate members, one of which forms a skid, said unit being oblong and embracing a U-shaped member mounted transversely thereof, a main plane frame support, a steering plane frame, a brace rod parallel with said support, all of said members being in a common vertical plane, all of said members being integrally connected. 110 115
- In testimony whereof I affix my signature in the presence of two witnesses.
